JAMES M. HAIT, OF LOS ANGELES, CALIFORNIA

MEANS FOR POSITIONING IMPELLERS IN BOWLS OF DRILLED WELL ROTARY PUMPS

Application filed August 26, 1931. Serial No. 559,408.

This invention relates to drilled well rotary pumps and deals with a means for accurately positioning the impellers in the bowls of such pumps.

5 In pumps of this nature it is known that the impeller or, in the case of a multiple unit pump, the impellers, must be accurately positioned within their respective bowls in order to produce an efficient pump and avoid 10 other objectionable features to be hereinafter mentioned.

A pump of this nature, broadly speaking, comprises a plurality of bowls interconnected in a conventional manner with a line shaft 15 extending through the bowls and having impellers mounted upon the shaft and so located upon the shaft as to revolve in each bowl. The usual shop practice is to fit each impeller with a certain amount of vertical movement 20 in the bowl generally termed "lateral." However, in deep wells where a considerable length of line shaft is used, the thrust load caused by the lifted weight of fluid causes 25 the impellers to lower to some indeterminate position, which not only may lower the efficiency of the pump but oftentimes introduces friction by the impellers riding upon the bowls.

30 A large percentage of this reduction in efficiency is caused by the lack of registration of the impeller port with the port in the bowl which is brought about by relative movement of the impeller with respect to the bowl. In order to overcome this, certain 35 types of pumps have been produced with the port in the impeller of larger vertical dimension than the port in the bowl. This, however, will be recognized as an inherent defect in the design of a pump of this nature 40 since it is known that if the port in the impeller and the port in the bowl are of identical dimensions and are operated in exact registration, the pumping efficiency is materially increased.

45 It is the purpose of this invention to provide means for overcoming the above mentioned objectionable features in pumps of the character described. The present invention deals with subject matter similar to 50 that of my co-pending application Serial

No. 512,763, filed February 2, 1931, entitled "Means for vertically positioning the shaft in a rotary pump", and provides an improvement in the means for such a purpose. Broadly speaking, the means employed consists of an electrical circuit having indicating means on the surface which operate to indicate when the shaft with the impellers for any reason lowers with respect to the bowls. The means employed for this purpose comprises a source of potential, preferably a battery, and a single conductor leading from said source of potential to a contact terminal positioned relatively close to the bowls and impeller, and in actual practice is preferably placed below the lower end of the shaft in the lower end of the bearing for the shaft. The circuit is completed through the shaft or the pump tubing to the surface. On the surface I provide a visual or an audible indicator, or both, if desired, for indicating when the circuit is closed. The advantages of such an arrangement evidently lie in the fact that the shaft may be accurately positioned when running under full load and the response of the system is immediate and definite, which enables the operator to definitely determine any misadjustment of the impellers in the bowls. I am aware that in certain wells the fluid handled may contain ingredients which would render the fluid as a fair conductor of electricity. Since in practice it is necessary to place the contact terminals a short distance apart in order to permit of slight movement only of the impellers with respect to the bowls, any conductivity of the well fluid might be objectionable. I therefore propose in one form of my invention to maintain the contact terminals in a dry pocket. In another form wherein the well fluid would introduce no objection as to conductivity, I provide contact points which may operate directly in the fluid or, in case the bearing is lubricated, may operate in the lubricant supplied to the bearing.

The objects of this invention, therefore, are to provide an electrical system for positioning impellers in bowls of drilled well pumps and to provide an arrangement of

contacts for this purpose. Other objects and advantages will become apparent as the description proceeds in conjunction with the drawing, in which:

5 Fig. 1 is a vertical elevation partly in section showing how my invention would be applied in an installation of a pump of the character described;

10 Fig. 2 is an enlarged vertical section showing one form of my contact arrangement;

15 Fig. 3 is a view similar to Fig. 2 showing another form of my contact arrangement; and

20 Fig. 4 is a horizontal section taken on line 4—4 of Fig. 2.

25 Referring to Fig. 1 wherein I have illustrated my invention in conjunction with a pump of the character described, A designates the power head, B the casing in the well, C the discharge conduit leading from the pump, D the shaft protective tubing and E the shaft driven by the power head. For the purposes of illustration I have shown a plurality of pump bowls generally designated F. These pump bowls are connected to the discharge conduit C by means of a special top fitting 11 and in turn support a suction pipe 12 having a strainer 13 on the lower end 30 thereof by means of a base fitting 14. It is to be understood that the base fitting 14 carries the bearing for the lower end of the shaft E and that my invention may be embodied in this fitting or the fitting 11. Also extending 35 down the well within the casing B and externally of the discharge fitting C, I provide a conductor 15 which is properly insulated for the purpose. The conductor 15 for purposes of illustration is shown as extending 40 to and entering the base fitting 14 at its lower end and as passing through the base plate 16 of the power head A, after which it is conveniently connected in any suitable manner to a conductor 17 which leads to a 45 potential source 18 (preferably a battery). The circuit continues through a switch 19, an indicator 20 which may be an ammeter or an audible indicator, back to the casing of the power head A and is attached thereto as 50 shown at 21. The circuit is thus seen to extend from the source 18 through the conductor 17 down to the base fitting 14 by means of the conductor 15, through contact points diagrammatically illustrated and designated 55 22, then up through the shaft E or the associated conduits of the pump and back to the casing of the power head A, from where it returns through the indicator 20 and the switch 19 to the source 18. The switch 19 is 60 incorporated for breaking the circuit when the detecting system is not in use and thus preventing possible electrolysis and corrosion of the contact points. The form of the contact members 22 shown in Fig. 2 will now be 65 described. This form has been designed to

operate in a dry condition or more specifically in an air pocket formed in the lower end of the shaft E. It is evident that the air pocket may be formed integrally with the shaft or 70 may be a cup-shaped member attached to the shaft. As shown in this view the fitting 14 has a central hub 14' supported therein by means of web members 23. The hub 14' is bored to take a bushing 24 which in turn provides a bearing for the lower end of the 75 shaft E. As shown, the lower end of the shaft is formed with a downwardly opening pocket 25 and in the upper transverse wall 26 of the pocket a suitable contact member 27 is screwthreadedly mounted. A lower contact member 28 is yieldably supported upon an insulation member 29 by means of a spring 30. The yieldably supported contact member permits the shaft to lower beyond the 80 point of contact without bringing the full load of the shaft upon the contact points, and thus preserves their usefulness. The contact member 28 is connected to the conductor 15, which extends through an upper hollow portion 29' of the member 29 outwardly through 85 an aperture 30 into a passage 23' in one of the webs 23 and upwardly to the surface, as before stated. Means are provided for mounting the member 29 in the lower end of the hub 14', such means preferably consisting of a nut 32 screwthreadedly mounted in the lower end of the hub 14' as shown at 33 and provided with a smooth bore 34 through which the member 29 is adapted to slidably move. A set screw 32' provides the means of 90 positioning the member 29 in the nut 32. This structure permits that the nut 32 may be securely fixed in place, after which the member 29 may be properly adjusted. In practice the member 29 is adjusted so that the contact members 27 and 28 will engage before the impellers and the bowls contact in case the shaft stretches. This adjustment would be made when the impellers are positioned in the bowls and would be done in 95 the shop when the pump is assembled.

100 It will be appreciated that in the pocket 25, no matter whether lubricant or water is used to lubricate the shaft E in the bushing 24, a pocket of air will be maintained at the upper end, as shown by the line X—X, which will always keep the contact points 27 and 28 dry.

105 In the form shown in Fig. 3 there is no pocket on the end of the shaft E and in this form the yieldable contact point may be placed upon the lower end of the shaft instead of upon the lower terminal. In this view, 14 designates the regulation base fitting and 14' indicates the hub supported by 110 the webs 23. The shaft E rotates within the hub 14' and the bushing 24 is provided to form a suitable bearing. On the lower end of the shaft E, I mount a screw-threaded nut 35. The nut 35 is hollowed in its upper end 115 120

125 130

as shown at 36 and contains a contact pin 37 slidably mounted therein and having a head 38 adapted to slidably fit within said hollowed portion 36. Above the head 38 of the pin 37, I provide a compression spring 39 held therein by means of a screwthreaded member 40 mounted in the upper end of the hollow portion 36. This structure will be recognized as providing a yieldably extending pin 37. The lower contact member comprises the insulation member 29 having the upper hollow portion 29' into which is fixedly mounted a contact pin 43. The conductor 15 is attached to the pin 43 and extends 15 outwardly through the aperture 30 and through the passage 23' in one of the webs 23 in the same manner as described with respect to Fig. 2. The member 29 is adjustably mounted in the lower end of the hub 14' in 20 a manner identical to that described in Fig. 2 and comprises the nut 32 screwthreadedly mounted therein as shown at 33 and having a smooth bore 34. The set screw 32' serves to hold the insulation member 29 adjustably 25 fixed within the bore 34. This form, as before stated, is adapted to operate under wet conditions, that is, the contact points 37 and 43 may be submerged either under lubricant or well fluid.

30 In using my invention the pump would be installed in the usual manner with the electrical circuit incorporated as described. After the installation and while the pump was running under full load, the shaft would 35 be lowered until the circuit was closed. This would indicate that the impellers were too low in the bowls, since the contact points had been previously set in the shop with a certain spacing. The shaft would then be raised 40 until the prescribed spacing of the contact points had been obtained and the pump would be there set to operate at full efficiency. If, for any reason, the shaft again lowers more than the spacing of the contact points, 45 the contact points will engage and close the circuit, which will be indicated on the surface and the shaft may again be raised into proper position. The advantages of electrically indicating when the shaft is out of 50 proper position are obvious and reside largely in the immediate and definite response of such a means together with the accuracy obtainable by such immediate response. The economy of such a system and the ease of 55 operation especially in deep wells are also to be considered as important factors of my invention.

The invention as above described has all the advantages hereinbefore pointed out and 60 is highly efficient in operation. Although I have shown and described my invention as embodying two forms, nevertheless I am aware that other forms may be devised which would depart from the specific structure 65 shown but which would depend for opera-

tion upon the principle embodied in this invention. I therefore intend this disclosure to include all such forms of the principle disclosed which come within the scope of the disclosure and the purview of the appended 70 claims.

I claim as my invention:

1. In a pump of the character described: a vertical shaft having impellers mounted thereon, said shaft having a downwardly 75 opening pocket at the lower end thereof; bowls corresponding to the impellers and means for positioning said impellers in said bowls, said means comprising an open electrical circuit having spaced contact members disposed within said pocket, said contact members being adapted to close said circuit upon the lowering of said shaft; and means for indicating when said circuit is 80 closed. 85

2. In a pump of the character described: a vertical shaft having impellers mounted thereon, said shaft having a downwardly opening cup at the lower end thereof; bowls 90 corresponding to the impellers and means for positioning said impellers in said bowls, said means comprising an open electrical circuit having spaced contact members disposed within said cup, said contact members being adapted to close said circuit upon the 95 lowering of said shaft, one of said contact members being yieldably supported; and means for indicating when said circuit is closed. 100

3. In a pump of the character described, a vertical shaft, a base fitting for said shaft forming a chamber below the lower end of said shaft, impellers mounted on said shaft, bowls corresponding to the impellers, a bushing in said base fitting closing said 105 chamber, an electric contact member carried on said shaft, an insulated contact member carried on the bushing extending into said chamber, and electrical means operable on closing of said contacts in said chamber. 110

4. In a pump of the character described: a vertical shaft; a base fitting for said shaft forming a chamber below the lower end of said shaft; impellers mounted on said shaft; bowls corresponding to the impellers; closure means in said base fitting closing said 115 chamber; an electric contact member carried on said shaft; an insulated contact member supported by said base fitting and extending into said chamber; and electrical means operable on closing of said contacts in said chamber. 120

5. In a pump of the character described: a vertical shaft; a base fitting for said shaft forming a chamber below the lower end of said shaft; impellers mounted on said shaft; bowls corresponding to the impellers; closure means in said base fitting closing said 125 chamber; an electric contact member carried on shaft; another electric contact member 130

- supported by said base fitting and having a contact surface in substantial alignment with said first mentioned contact member; insulating means for maintaining a non-
5 conductive relation between said contact members except when they are in engagement with each other; and electrical means operable on inter-engagement of said contact members.
- 10 6. In a pump of the character described: a suspended shaft having impellers mounted thereon; bowls corresponding to the impellers; a fitting chambered so as to surround a part of the suspended portion of
15 said shaft near the lower end thereof; means for positioning said impellers in said bowls comprising an open electrical circuit having spaced contact members disposed within said chambered fitting, said contact members
20 being adapted to close said circuit upon the lowering of said shaft; and means for indicating when said circuit is closed.

In testimony whereof, I have hereunto set my hand at Los Angeles, California, this
25 19th day of August, 1931.

JAMES M. HAIT.
